UNITED STATES PATENT OFFICE.

WOODSON C. TUCKER, OF BENHAM, KENTUCKY, ASSIGNOR TO INTERNATIONAL HARVESTER COMPANY OF NEW JERSEY, A CORPORATION OF NEW JERSEY.

BLASTING-ROD.

1,192,958.

Specification of Letters Patent.

Patented Aug. 1, 1916.

Application filed July 13, 1914. Serial No. 850,625.

To all whom it may concern:

Be it known that I, Woodson C. TUCKER, a citizen of the United States, residing at Benham, in the county of Harlan and State 5 of Kentucky, have invented certain new and useful Improvements in Blasting-Rods, of which the following is a full, clear, and exact specification.

This invention relates to blasting rods.

- 10 The object of my invention is to improve blasting rods, making them more simple, compact, and providing them with coöperating parts so related as to meet all of the requirements for successful commercial use.
- 15 This object is accomplished by providing an expandible member or shell, an actuator within said shell, and means actuated by said actuator for expanding said expandible member, and an expansion ring surrounding 20 said shell acting in opposition to said means.

The invention is illustrated on the accompanying sheet of drawings, in which—

- Figure 1 is a longitudinal sectional view 25 of my improved blasting rod; Figs. 2, 3, 4 and 5 are sectional views taken respectively in the planes of lines 2—2, 3—3, 4—4 and 5—5 of Fig. 1; and Fig. 6 is a fragmentary enlarged sectional view of my blasting rod showing parts of the shell expanded by the 30 expansion means.

The various novel features of my invention will be apparent from the description and drawings, and will be particularly pointed out in the appended claims.

- 35 My improved blasting rod includes an expandible shell 10 including a plurality of radially movable members 11 having a central hollow portion 12 for the reception of an actuator or threaded member 13 having 40 a handle 14, by means of which said actuator or member may be actuated. Said shell 10 is provided with recesses 15 for the reception of internally threaded expansion blocks 16, which surround the threaded actuator 13 45 and travel thereon when the said threaded actuator is rotated. These expansion blocks

16 are wedge-shaped, and portions 17 thereof are adapted to pass into engagement with the inclined walls 18 of the recesses 15 for expanding the shell or expandible member 50 10 when it is desired so to do. This shell 10 is provided with a plurality of exterior annular grooves 19 in which are located expansion rings 20, which act in opposition to the expansion blocks 16 to hold the expansion 55 member or the parts thereof in their innermost position. One end of the shell is provided with a copper cap 21 to avoid the possibility of ignition by sparks produced by friction in inserting the blasting rod in a 60 drill hole.

Surrounding the actuator 13 is a collar 22 which is secured to the actuator by a set screw 23 for limiting the inward movement of said actuator. This actuator is provided 65 with an opening 24 extending therethrough for the reception of a fuse or electric wires, or for the use of a squib for igniting purposes.

By means of this arrangement after the 70 hole has been drilled and the powder inserted therein, this blasting rod may be quickly introduced into the hole, the outer shell thereof expanded, and the charge fired in the minimum amount of time and with the 75 greatest amount of safety, rendering blasting simple, inexpensive and safe in operation.

There may be various modifications of the arrangement herein shown and described, 80 and it is my intention to cover all such modifications which do not involve a departure from the spirit and scope of my invention as set forth in the appended claims.

What I claim is:

1. A blasting rod comprising the combination of an expandible shell having a cylindrical opening therethrough changing at intervals into cone-shaped openings with hyperbolically formed sides, a threaded actuator extending through said openings, and wedge expansion members within said

cone-shaped openings coöperating with said sides and mounted on and actuated by said actuator for expanding said shell.

2. A blasting rod comprising the combination of an expandible shell having a cylindrical opening therethrough changing at intervals into cone-shaped openings, an actuator extending through said openings, and wedge expansion members within said cone-

shaped openings actuated by said actuator 10 for expanding said shell.

In testimony whereof I affix my signature, in the presence of two witnesses.

WOODSON C. TUCKER.
